WALL-MOUNTABLE LAMP

Charles E. Gregg, Fredericktown, Ohio, assignor to The Gregg Manufacturing Company, Fredericktown, Ohio, a corporation of Ohio

Filed Apr. 8, 1965, Ser. No. 84,675

Term of patent 3½ years

(Cl. D48—4)

FIG. 1 is a perspective view of a wall-mountable lamp showing my new design;

FIG. 2 is a top plan view thereof;

FIG. 3 is a side elevational view thereof;

FIG. 4 is a rear elevational view thereof.

The lamp shade and light bulb shown in broken lines in FIG. 1 are for purposes of illustration only, and form no part of the present design.

I claim:

The ornamental design for a wall-mountable lamp, substantially as shown and described.
